PAPER FASTENER

Chester I. Wagner, Brooklyn, N. Y., assignor to
 Safety Fastener Co., Bloomfield, N. J., a corporation of New Jersey

Application November 12, 1938, Serial No. 240,032

20 Claims. (Cl. 24—153)

This invention relates to a paper fastener and has special reference to a device for fastening papers such as letters, pamphlets, newspapers, magazines and similar articles in book form for 5 filing or the like.

More particularly, this invention relates to a paper fastener comprising a base having a prong for each end thereof with each of the prongs comprising a wire looped back upon itself in a 10 spaced relation, the looped end of each of said prongs being adapted to be inserted through apertures in the paper to be fastened. Means are provided for securing the open ends of the prongs to the base with other means on the base for 15 maintaining the spaced relation of the wire of each of said prongs.

It is also contemplated by the present invention to provide a compressor for co-operation with the base, the looped end of each of the 20 prongs being adapted to be bent inwardly toward each other over the compressor, the compressor having means preferably comprising spaced notches at the ends thereof for co-operating with the above-mentioned means of the 25 base for maintaining the spaced relation of the wire of each of the prongs.

Heretofore, so far as applicant is aware, the prongs of the usual paper fastener of the type above described have been formed integrally or 30 detachably with a sheet metal base, the prongs being likewise of sheet metal. Both the base and the prongs therefor have been stamped of sheet metal and burred edges are inescapable in the operation on flat metal where, as in the 35 present instance, cost of manufacture is to be held to a minimum. Correspondents and file clerks in the instance of handling these sheet metal prongs and bases have had to risk acquiring cut, scratched or unsightly fingers from 40 the usual burred edges thereof and danger of infection and serious disablement has been an ever present peril.

The present application contemplates the use of a prong for each end of the base, the prong 45 comprising a wire looped back upon itself in a spaced relation. Such a construction with its smooth edges apparently is the only practical elimination of burred prongs and contributes a safety factor in the use of paper fasteners.

50 Another danger ever present when flat metal prongs are used with the resultant burred edges, is injury sustained when sliding a lock on or off one prong by snagging or jagging the fingers by contact with the often raised point of the 55 adjacent prong. The looped comparatively blunt

wire end absolutely eliminates this hazard while serving in the same capacity as the pointed sheet metal prong to facilitate the insertion of the prong into the apertures of the papers.

The use of a prong for each end of the base 5 with the prong being detachably secured to the base in an extremely simple manner permits prongs to be quickly changed so that prongs of one, two or more inch capacity are interchangeable when and if more than a minimum amount 10 of bulk has accumulated in any one file. The practice of buying complete fasteners with attached prongs is, of course, generally wasteful and inconvenient and the use of detachable prongs with a simple and convenient method of 15 attaching the prongs to the base affords a maximum of economy. The purchaser may stock a substantial number of bases, compressors and prongs, with the proportional number of shorter prongs being greater than the number of longer 20 prongs, whereafter it will be more convenient to file the papers to be fastened on the shorter prongs until actual growth of some of the files may demand greater capacity when the prongs of more substantial length may be substituted, 25 the bases and compressors being retained.

One of the objects of this invention is to provide a paper fastener of the type indicated above which will afford a maximum of safety in the use thereof thus eliminating danger of infection 30 and serious disablement.

Another object of this invention is to provide a paper fastener of the type indicated above having a wire looped back upon itself to provide a threading point which is comparatively blunt 35 and will not cut or scratch the fingers when the usual lock is employed to clamp the prong against the compressor.

It is also an object of this invention to provide a paper fastener of the character herein- 40 above noted in which each prong is easily and conveniently snapped on or detached from the base for purposes of interchangeability of prongs and convenience of use.

Other objects and advantages will hereinafter 45 be more particularly pointed out and for a more complete understanding of the characteristic features of this invention, reference may now be had to the following description when read together with the accompanying drawings, in 50 which latter:

Figure 1 is a plan elevational view of a paper fastener incorporating the features of this invention, the paper fastener being shown in use 55

in fastening papers which latter are shown fragmentarily;

Fig. 2 is a longitudinal sectional view taken on the line 2—2 of Fig. 1;

Fig. 3 is a perspective view of the fastener assembly prior to the locking of the prongs in position over the compressor;

Fig. 4 is a plan elevational view of a fragmental portion of a base disclosing in detail the manner in which the prong shown partially in section is fastened to the base;

Fig. 5 is a sectional view taken on the line 5—5 of Fig. 4;

Fig. 6 is a view similar to Fig. 4 showing a modified form of prong construction;

Fig. 7 is a perspective view similar to Fig. 3 showing a modified form of compressor; and

Fig. 8 is a view similar to Fig. 7 showing a still further modified form of compressor.

Referring now to the drawings and more particularly to Figs. 1 to 5, inclusive, thereof, the paper fastener shown therein incorporating the features of this invention comprises a base 10 having prongs 11 and 12 secured thereto, one for each end of the base, and a compressor 13 for co-operation with the prongs and the base.

The base 10 is elongated and is preferably formed of thin sheet metal. Longitudinally extending embossments 13 and 14 are formed intermediate the width of the base adjacent each end thereof, the side walls of the embossment preferably being continuous and communicating with each other as shown more particularly in Fig. 3. The material of the base 10 intermediate the embossments 13 and 14 may preferably be embossed at 15 for purposes of strength and, although not necessary, may be desirable. Each of the embossed portions 13 and 14 of the base 10 is provided with an ear 16 and 17, respectively, 40 the ears being bent to form laterally extending pockets 18 and 19. The ears are preferably cut and deformed from the material of the base 10 within the embossed portions and one end of each of the embossed portions 13 and 14 has an opening 45 20 and 21 respectively.

Each of the prongs 11 and 12 are formed of a wire looped back upon itself in a spaced relation to provide a looped end 22 and 23. The wire may be of any usual size and type and is preferably of round cross section. The open end of the prong is secured to the base while the looped end extends therefrom and is adapted to be inserted through apertures in the paper or articles to be fastened.

Referring now more particularly to Fig. 4 of the drawings, the open end of the prong is shown in one specific manner of being attached to the base, portions 24 adjacent the ends of the looped wire being bent inwardly in a direction toward each other into the laterally extending pocket 19 of the ear 17. The width of the ear 17 is substantially less than the inside width of the embossment 14, whereby the edges of the ear occupy a spaced relation with respect to the side walls 55 of the embossment. The spaced relation above noted is sufficient to readily receive the thickness of the wire of the prong and the side walls of the embossment serve to hold the bent portions 24 of the prong against displacement from the 60 pocket 19.

In order to assemble the prongs on the base, the open end of the prong is inserted through the opening 21 whereafter the spaced portions thereof together with the bent portions 24 thereon are 75 sprung apart so as to be received in the pocket 19

as the ear 17 occupies a position extending out of the embossment as shown in dotted lines in Fig. 3. After the portions 24 are inserted in the pocket 19, the ear 17 is bent down into the position within the embossment 14 as shown in full 5 lines in the drawings. It may be desirable to form the tip ends 12a of the prong in a direction inwardly toward each other within the embossment although this may be done if and as desired.

The end edges of the base 10 are provided with spaced notches 25 and 26 and after the prongs 11 and 12 are secured in position with respect to the base the prongs are bent at substantially right angles to the base into the notches so that the 10 prongs are maintained in a spaced relation.

The compressor 13 is formed preferably of an elongated strip of sheet metal having longitudinally extending guides along each side edge in the form preferably of a channel produced by 20 forming flanges 27 and 28 from the material of the strip inwardly in a direction toward each other and in a spaced relation with the main body portion of the strip. A pair of latching members 29 and 30 slidably engage the channels 25 formed by the bent over flanges 27 and 28, each of the latching members comprising a raised portion having laterally extending corrugations with side flanges 29a and 30a, respectively, received in the channels. The end edges of the flanges 27 30 and 28 are depressed as at 27a and 28a, respectively, into engagement with the main body portion so as to prevent the latching members 29 and 30 from displacement from the channels.

The compressor is provided with U-shaped 35 openings 31 and 32 adjacent each end thereof for receiving the looped ends of the prongs 22 and 23, respectively. The legs 31a and 31b, and 32a and 32b of the U-shaped openings 31 and 32, respectively, form spaced notches for co-operation 40 with the notches 25 and 26 of the base to maintain the spaced relation of the wire of each of the prongs 11 and 12 when the prongs are bent over in a direction toward each other against the compressor 13. In order to maintain the relation 45 of the bent over ends of the prongs to the compressor, the slides 29 and 30 are moved over the prongs, the latter being preferably provided with raised portions 33 for engaging the corrugations of the latching members to provide an interlock- 50 ing resilient engagement therebetween.

Referring now more particularly to Fig. 6 of the drawings, a modified form of prong is shown for association with the base described above. The prong 12a comprising a wire looped back upon itself in a spaced relation, instead of having bent portions near its end formed back upon themselves as in Fig. 4, has the bent over portions 24a crossing each other within the pocket 19a of the ear 11a. The open end of the wire is inserted 60 through the opening 21 at the end of the embossed portion 14 to a position such that the crossed portions 24a are forward of the ear 11a which latter is in a raised position. The crossed portions 24a are then moved in a direction toward 65 the opening 21 below the ear and into the pocket 19a after which the ear 11a is bent back into its lowered position within the embossment.

Referring now more particularly to Fig. 7 of the drawings, a modified form of compressor 34 70 is shown in which the latching means for holding the ends of the prongs 11 and 12 against the compressor have been modified. The compressor is formed of an elongated strip of sheet metal and is reinforced by the provision of longitu- 75

dinarily extending embossments 35 and 36 adjacent the side edges thereof substantially over the full length thereof. Instead of the usual guide members forming a channel for receiving 5 5 slideable latching members therein, flanges 37 and 38 are cut and deformed from the material of the compressor on opposed sides and adjacent opposed ends, each of the flanges extending preferably less than midway of the compressor.

10 The flanges 37 and 38 are elevated from the main body portion a sufficient distance to permit the reception of one side of the prong, and lips 39 and 40 are provided, respectively, on the flanges 37 and 38 for preventing accidental 15 placement of the prongs from beneath the flanges. Each of the lips is curved downwardly to extend below the level of the flange and is preferably resilient to provide an interlocking resilient engagement with the prongs so that the latter may 20 be readily detached therefrom when desired.

As above stated, the compressor is merely modified to disclose a type of latching means which may desirably be used in connection with the form of wire loop disclosed in the present 25 invention. The base and prongs disclosed in Fig. 7 are the same as the corresponding members in the previously illustrated and described figures and the functions thereof are likewise the same.

Referring now more particularly to Fig. 8 of 30 the drawings, a still further modified form of compressor is disclosed, the compressor 41 being preferably formed of an elongated strip of sheet metal having an opening 42 at one end thereof for receiving the looped end of the prong 11. 35 Each end edge of the compressor is provided with notches 43 and 44 for receiving and maintaining in a spaced relation the wire of each of the prongs 11 and 12. The prong 12 is bent over and against the upper surface of the compressor 40 41 while the prong 11, as above stated, extends through the opening 42 and thence below the compressor, the compressor being threaded onto the prong 11 and the assembly thereof being bent over prior to the time at which the end of 45 the prong 12 is bent over the other end of the compressor.

In order to maintain the end of the prong 12 in its position against the compressor, a finger 45 is preferably cut and deformed from the material of the compressor, the end of the finger being bent slightly downwardly so as to provide an interlocking resilient engagement with the prong, the prong being readily removable from its interlocking engagement with the finger.

50 55 While several embodiments of this invention are herein shown and described, it is to be understood that various modifications thereof may be apparent to those skilled in the art without departing from the spirit and scope of this invention and, therefore, the same is only to be limited by the scope of the prior art and appended claims.

I claim:

1. A paper fastener comprising a base, a prong 60 for each end of said base, each of said prongs comprising a wire looped back upon itself in a spaced relation, the looped end of each of said prongs being adapted to be inserted through apertures in the paper to be fastened, means for securing the open ends of said prongs to said base, and other means on said base for maintaining the spaced relation of the wire of each of said prongs.

2. A paper fastener comprising a base, a prong 70 75 for each end of said base, each of said prongs

comprising a wire looped back upon itself in a spaced relation, the looped end of each of said prongs being adapted to be inserted through apertures in the paper to be fastened, means for securing the open ends of said prongs to said base, and spaced notches on said base for receiving spaced portions of the wire of each of said prongs and for maintaining the spaced relation thereof.

3. A paper fastener comprising a base having 10 spaced openings one at each end, a prong for each end of said base, each of said prongs comprising a wire looped back upon itself in a spaced relation, the looped end of each of said prongs being adapted to be inserted through apertures in the 15 paper to be fastened, means for securing the open end of said prongs to said base, the ends of said base having spaced notches for receiving spaced portions of the wire of said prongs and for maintaining the spaced relation thereof, the looped 20 ends of said prongs extending through said openings.

4. A paper fastener comprising an elongated base having spaced ears one at each end, a prong for each end of said base, each of said prongs 25 comprising a wire looped back upon itself in a spaced relation, the looped end of said prong being adapted to be inserted through apertures in the paper to be fastened, said ears forming laterally extending pockets for receiving portions of 30 said prongs adjacent the open ends thereof for attachment of said prongs to said base, and means on said base for maintaining the spaced relation of the wire of each of said prongs.

5. A paper fastener comprising a base having 35 embossed portions at each end, an ear within each of said embossed portions, a prong for each end of said base, each of said prongs comprising a wire looped back upon itself in a spaced relation, the looped end of said prong being adapted 40 to be inserted through apertures in the paper to be fastened, said ears forming laterally extending pockets for receiving portions of said prongs adjacent the open ends thereof for attachment of said prongs to said base, said embossments 45 preventing displacement of said prongs from said ears, and means on said base for maintaining the spaced relation of the wire of each of said prongs.

6. A paper fastener comprising a base having embossed portions at each end, an ear formed in- 50 tegrally on said base within the embossed portions, a prong for each end of said base, each of said prongs comprising a wire looped back upon itself in a spaced relation, the looped end of said prong being adapted to be inserted through aper- 55 tures in the paper to be fastened, said ears forming laterally extending pockets for receiving bent portions of said prongs from each side thereof for attachment of said prongs to said base, the side walls of said embossments extending adjacent the 60 portions of said prongs at the bent portions to prevent displacement of said prongs from said ears, and means on said base for maintaining the spaced relation of the wire of each of said prongs.

7. A paper fastener comprising a base having 65 embossed portions adjacent each end thereof and an opening at one end of each embossment, an ear formed integrally on said base within each embossment, a prong for each end of said base, each of said prongs comprising a wire looped back 70 upon itself in a spaced relation, the looped end of said prong being adapted to be inserted through apertures in the paper to be fastened, the open ends of said prongs being secured to said base by said ears and being held from displacement from 75

- said ears by said embossments, the looped ends of said prongs extending from said ears through said openings, and means on said base adjacent said openings for engaging and for maintaining the spaced relation of the wire of each of said prongs.
8. A paper fastener comprising an elongated base having longitudinally extending embossed portions intermediate the width of the base adjacent each end thereof, each of said embossed portions having an opening at one end thereof, an ear formed integrally on said base within each embossment, a prong for each end of said base, each of said prongs comprising a wire looped back upon itself in a spaced relation, the looped end of said prong being adapted to be inserted through apertures in the paper to be fastened, the open ends of said prongs being secured to said base by said ears and being held from displacement from said ears by said embossments, the looped ends of said prongs extending from said ears through said openings, and notches on the end edges of said base into which said prongs are bent for maintaining the spaced relation of the wire of each of said prongs.
9. A paper fastener comprising an elongated base having an ear formed integrally with said base one adjacent each end thereof and an opening adjacent each ear, a prong for each end of said base, each of said prongs comprising a wire looped back upon itself in a spaced relation, the looped end of said prong being adapted to be inserted through apertures in the paper to be fastened, and notches on the end edges of said base, said ears forming laterally extending pockets for receiving bent portions of said prongs extending in a direction toward each other, the looped ends of said prongs extending from said ears through said openings and being bent into engagement with said notches for maintaining the spaced relation of the wire of each of said prongs.
10. A paper fastener comprising an elongated base having longitudinally extending embossed portions intermediate the width of the base adjacent each end thereof, each of said embossed portions having an opening at one end thereof, an ear formed integrally on said base within each embossment, a prong for each end of said base, each of said prongs comprising a wire looped back upon itself in a spaced relation, the looped end of said prong being adapted to be inserted through apertures in the paper to be fastened, and notches on the end edges of said base, said ears forming laterally extending pockets for receiving bent portions of said prongs extending inwardly in a direction toward each other, said embossments holding said bent portions against displacement from said pockets, the looped ends of said prongs extending from said ears through said openings and being bent into engagement with said notches for maintaining the spaced relation of the wire of each of said prongs.
11. A paper fastener comprising a base, a prong for each end of said base, a compressor, each of said prongs comprising a wire looped back upon itself in a spaced relation, the looped end of each of said prongs being adapted to be inserted through apertures in the paper and then bent inwardly toward each other over said compressor, the open ends of said prongs being secured to said base, and means on said base and said compressor for maintaining the spaced relation of the wire of each of said prongs.
12. A paper fastener comprising a base, a prong for each end of said base, a compressor, each of said prongs comprising a wire looped back upon itself in a spaced relation, the looped end of each of said prongs being secured to said base, and spaced notches on said base and on said compressor for engaging and for maintaining the spaced relation of the wire of each of said prongs.
13. A paper fastener comprising a base having spaced openings one at each end, a prong for each end of said base, a compressor, each of said prongs comprising a wire looped back upon itself in a spaced relation, the looped end of each of said prongs being adapted to be inserted through apertures in the paper and then bent inwardly toward each other over said compressor, the open ends of said prongs being secured to said base, spaced notches at the ends of said base adjacent said openings, the looped ends of said prongs extending through said openings, and means on said compressor co-operating with said spaced notches for engaging and for maintaining the spaced relation of the wire of each of said prongs.
14. A paper fastener comprising a base, a prong for each end of said base, and a compressor having spaced notches at each end thereof, each of said prongs comprising a wire looped back upon itself in a spaced relation, the looped end of each of said prongs being adapted to be inserted through apertures in the paper and then bent inwardly toward each other into said notches and over said compressor, the open ends of said prongs being secured to said base, the material bounding the notches on said compressor maintaining the spaced relation of the wire of each of said prongs.
15. A paper fastener comprising a base, a prong for each end of said base, a compressor having spaced notches at each end thereof, each of said prongs comprising a wire looped back upon itself in a spaced relation, the looped end of each of said prongs being adapted to be inserted through apertures in the paper and then bent inwardly toward each other into said notches and over said compressor, the open ends of said prongs being secured to said base, and hook-shaped portions on said compressor for detachably receiving the bent over portions of the prongs, the material bounding the notches on said compressor maintaining the spaced relation of the wire of each of said prongs.
16. A paper fastener comprising a base, a prong for each end of said base, a compressor having substantially U-shaped openings one at each end, each of said prongs comprising a wire looped back upon itself in a spaced relation, the looped end of each of said prongs being adapted to be inserted through apertures in the paper and the U-shaped openings and then bent inwardly toward each other over said compressor, the open ends of said prongs being secured to said base, and means on said compressor for holding said looped ends thereagainst, the material bounding the U-shaped openings on said compressor maintaining the spaced relation of the wire of each of said prongs.
17. A paper fastener comprising an elongated base, a prong for each end of said base, a compressor having substantially U-shaped openings one at each end and longitudinally extending guides along each side, each of said prongs comprising a wire looped back upon itself in a spaced relation, the looped end of each of said prongs

being adapted to be inserted through apertures in the paper and the U-shaped openings and then bent inwardly toward each other over said compressor, latching means slidable on said 5 guides the open ends of said prongs being secured to said base, and means on said prongs providing interlocking resilient engagement with said latching means when said latching means is moved over said prongs, the material bounding the U-shaped openings of said compressor maintaining the spaced relation of the wire of each of said prongs.

18. A paper fastener comprising an elongated base, a prong for each end of said base, a compressor, each of said prongs comprising a wire looped back upon itself in a spaced relation, the looped end of each of said prongs being adapted to be inserted through apertures in the paper and then bent inwardly toward each other over 15 said compressor, the open ends of said prongs being secured to said base, and spaced notches on the end edges of each of said base and said compressor for engaging and for maintaining the spaced relation of the wire of each of said prongs.

19. A paper fastener comprising a base, a prong for each end of said base, a compressor having an opening at one end thereof and a hook-shaped member at the other end thereof, each of said prongs comprising a wire looped back upon itself 20 in a spaced relation, the looped end of one of

said prongs being adapted to be inserted through apertures in the paper and then through said opening and beneath said compressor, the looped end of the other of said prongs being adapted to be bent over said compressor inwardly toward the other of said prongs, the open ends of said prongs being secured to said base, and spaced notches on the end edges of each of said base and said compressor for receiving and for maintaining the spaced relation of the wire of each of said prongs. 25

20. A paper fastener comprising a base having an ear formed integrally with said base one adjacent each end thereof and an opening adjacent each ear, a prong for each end of said base, a compressor, each of said prongs comprising a wire looped back upon itself in a spaced relation, the looped end of each of said prongs being adapted to be inserted through apertures in the paper and then bent inwardly toward each other over said compressor, said ears of said base forming laterally extending pockets for receiving portions of said prongs for securing said prongs to said base, the looped ends of said prongs extending from said ears through said openings of said base, and spaced notches on the end edges 25 of each of said base and said compressor for receiving and for maintaining the spaced relation of the wire of each of said prongs.

CHESTER I. WAGNER. 30
